US0D1034249S

(12) **United States Design Patent** (10) **Patent No.:** **US D1,034,249 S**
(45) **Date of Patent:** **** Jul. 9, 2024**

(54) **CANISTER**

(71) Applicant: **Entech Instruments Inc.**, Simi Valley, CA (US)

(72) Inventor: **Daniel B. Cardin**, Simi Valley, CA (US)

(73) Assignee: **Entech Instruments Inc.**, Simi Valley, CA (US)

(**) Term: **15 Years**

(21) Appl. No.: **29/792,732**

(22) Filed: **Apr. 20, 2022**

Related U.S. Application Data

(63) Continuation of application No. 35/001,915, filed on Sep. 2, 2020 (U.S. filing date under 35 U.S.C. 384), and having an international filing date of Sep. 2, 2020, now abandoned.

(30) **Foreign Application Priority Data**

Mar. 2, 2020 (WO) 970045865
Sep. 2, 2020 (WO) 970066155

(57) **CLAIM**

The ornamental design for a canister, as shown and described herein.

DESCRIPTION

FIG. 1 is a front view of a canister;

FIG. 2 is a first perspective of a canister;

FIG. 3 is a top view of a canister;

FIG. 4 is a bottom view of a canister; and,

FIG. 5 is a second perspective of a canister.

The shading in the figures shows contour, not surface ornamentation.

1 Claim, 5 Drawing Sheets
